SIMON B. HESS, OF NEW YORK, N. Y.

ELECTRIC BURGLAR-ALARM.

1,320,857.

Specification of Letters Patent.

Patented Nov. 4, 1919.

Application filed September 21, 1915. Serial No. 51,752.

To all whom it may concern:

Be it known that I, SIMON B. HESS, a citizen of the United States, residing at New York, in the county of New York and State of New York, have invented certain new and useful Improvements in Electric Burglar-Alarms, of which the following is a specification.

This invention relates to electric burglar alarm systems of the class employed for the electric protection of banks, stores, lofts, buildings and the like, and a principal object of the invention is to provide a system which affords a great degree of protection. 10 Another object of this invention is to provide simple means for testing the system to ascertain if the wiring and connections are in working condition, and audible indicating means in connection with such testing means to assist in indicating the actual condition of the system. 15

It is still another object of this invention to provide a system which upon test will indicate a fault or trouble in the protective circuit, notwithstanding which it will be possible for the operator to set the system and obtain substantially the same degree of protection pending the correction of the fault, as though the fault did not exist. 25

It is a further object of this invention to provide a housing for an alarm signal arranged so as to start the signal in operation upon illegal interference with the alarm housing. 30

It is still another object of this invention to provide novel means of controlling the alarm circuit, to enable the person setting the system to leave the guarded structure by means of any exit, after setting the alarm, without actuating the signal. 35

This invention consists in the general combination of parts and details described hereinafter, all of which contribute to produce an effective burglar alarm system. 40

A preferred embodiment of my invention is described in the accompanying specification, while the broad scope of my invention is pointed out in the claims. 45

Referring now to the drawings, Figure 1 is a partially diagrammatic view of the complete system, showing the devices used to control its operation; Fig. 2 is a detail view of the testing device; Fig. 3 is a diagrammatic view of the connections of the testing device; Fig. 4 is a perspective view of the

front side of the instrument board, on the rear side of which are mounted the devices shown in Fig. 1, excepting the alarm casing and the circuit closer for the alarm; Fig. 5 is a fragmentary view of the bottom of the board shown in Fig. 4. 50

Like numerals of reference refer to like parts throughout the several views.

In the diagram illustrated in Fig. 1, a form of the system is shown in its normally operative set status, and the circuit may be traced as follows: beginning at the battery 1, through main wire 2, to junction 3 and after passing through the guarded structure 5 by means of wires 4 and 6 passes 70 through relay coils 7 and 8, to wire 9, which also passes through the guarded structure 5, to junction 10 and by means of wire 11 back to the battery 1. From the center of battery 1 there is connected to ground at 13 75 a wire 12; at 21 there is another ground, providing conducting means from the ground at battery 1 by means of wire 20, to junction 19, thence by wire 18, to test switch member 17 which is normally in contact with its coöperant contact member 16, thence by wire 15 to the junction 14, between the two relay coils 7 and 8. This ground lead and the two leads 4—6, and 9 constitute the twin protective circuits which 80 are the subject of my United States Patent No. 1,298,710, issued April 1, 1919. 85

A normally closed shunt for the protective circuit may be traced as follows: from the battery 1, by means of wire 2, to junction 3, thence by wire 28 to contact member 27, which is normally in engagement with armature lever 26 which acts as a conductor, to contact member 25, wire 24, to the lower relay coils 23, wire 22, to junction 10, wire 95 11, to the opposite pole of battery 1.

Now when a break occurs in a single conductor of the guarded structure, this will have no effect upon relay armature 55 for the reason that the ground connection 13 90 will provide conducting means whereby at least one of the two coils 7 and 8 will remain energized, notwithstanding such break, and the magnetic flux of the coils 7 and 8 is so calculated, that while one coil 10 is energized, the magnetic field will be sufficiently powerful to hold attracted armature 55. 100

As armature 55 is now in its attracted position with reference to coils 7 and 8 and 110

at the same time is in its retracted position with reference to coils 23, the pull of coils 7 and 8 will naturally be a maximum while the pull of coils 23 will be a minimum.

5 Additional adjustment may be obtained by any other well known means, such as selecting coils of different resistances, or having a different number of turns, etc.

Since the two coils 7 and 8 are connected 10 to the three wires 6, 9, and 15, these coils may be said to comprise a "three wire" electro-magnet.

The guarded structure is so wired with reference to the protective circuit that both 15 wires pass through all openings, so that both wires parallel each other throughout the premises, and when an interference therewith occurs both conductors will be interrupted, which will cause the deenergization 20 of both coils, 7 and 8. As current from the source of energy 1 is passing through the shunt circuit which includes relay coils 23, these coils will coöperate with the force of 25 gravity to attract armature 55 and will at the same time overcome the force of any residual magnetism remaining in relay coils 7 and 8, thereby positively attracting armature 55 and causing the same to break connection between its coöperant contact 73, 30 and make engagement with its lower coöperant contact 29, thereby closing a circuit and energizing one coil 35 of the circuit closer, which in turn actuates an armature to close the circuit of the signaling means, 35 as will be hereinafter described.

The circuit closer circuit may be traced as follows: from relay armature 55 which is now assumed to be in engagement with its coöperant contact 29, by means of wire 30, 40 to contact members 31 and 32 which are now in contact with each other by reason of the position of the contact piece 77, connected to lever 26 by insulating piece 78, thence by wire 33 to junction 34, to circuit 45 closer coil 35, wire 36, contact 37, armature 38, wire 39, junction 40, wire 41, to junction 42, thence by wire 72 to the alarm battery 43, to junction 44, wire 45, to junction 46, wire 47, lock switch member 48, which 50 is in contact with its coöperant switch member 49, thence by wire 50, to junction 51, wire 52, to junction 53, wire 54, to armature 55.

The closure of the circuit which has just been traced will cause the energization of 55 coil 35 which will attract toward itself armature 38, thus opening the circuit of the circuit closer and making engagement with contact 56, closing the circuit of the signaling means which may be traced as follows: from alarm battery 43, to junction 44, wire 61 to binding post 60 which is grounded on the frame of audible signal 59, thence by bell armature 90, to contact 91, to the coils of bell 59, to binding post 58 which is insulated from the bell structure, thence by

means of wire 57, circuit closer contact 56, armature 38, wire 39, junction 40, wire 41, junction 42, wire 72, to the opposite pole of battery 43, thus energizing the audible signaling means.

In order to stop the operation of the signal, let us assume that the combination lock 62 is properly manipulated and the bolt thrown to the "Day" side 93 so that the L-shaped member 63 is moved to its dotted line position 92, thereby opening the circuit connection between switch members 48 and 49 and creating a new circuit connection between switch members 48 and 64.

In Fig. 5, there is illustrated a plunger 80 in the bottom of the instrument casing. Let us also assume that this plunger has been pressed upward thereby moving the armature lever 26 to its dotted line position indicated at 97, thereby opening the associated circuits of contact members 31 and 32 and 25 and 27, and forming a circuit across contact members 75 and 76. This will energize the restoring coil 70 of the circuit closer and silence the signal. This circuit by means of which this result is attained may be traced as follows: from battery 43 by means of junction 44, wire 45, junction 46, wire 47, to switch member 48, which is now in engagement with its coöperant switch member 64, thence by wire 65, to contact 66, to its coöperant contact 67, wire 69, to restoring coil 70, wire 71, to junction 40, wire 41, junction 42, wire 72, to the opposite pole of battery 43, thus energizing coil 70 to 100 actuate circuit closer armature 38 to break engagement with 56, thereby opening the circuit of the audible signal.

Lock switch indicator arm 63 which passes through a slot 96 in instrument casting 99, (see Fig. 4) is now in its dotted line position as illustrated at 92, indicating that the system is connected on the "Day" side and that therefore the audible signal will not be actuated upon the occurrence of a change of status in the protective circuit.

Now assuming that the system is actually in the status just described, that is, not set for operation, the indicator pointing to "Day" and the armature lever 26 of circuit closer control electro-magnet 80 in its dotted line position 97, with all exits closed, and assuming the protective circuits to be complete, armature 55 will be in engagement with contact 73, there being no current in lower relay coils 23, thus forming a circuit which may be temporarily energized from either the manipulation of the combination lock in its movement to the "Night" or set side or by the operation of test button 84, by means of which test switch members 83 and 82 are brought into engagement with each other. This circuit is to be traced as follows: from upper contact 73, to wire 74, junction 19, wire 102, contact mem- 125

ber 75, contact piece 77, contact member 76, wire 79, to electro-magnet 80, wire 81, to junction 42, wire 72, to alarm battery 43, to junction 44, to wire 45, to junction 46, where 5 the circuit divides one branch going to test switch member 82 and one branch by means of wire 47 to lock switch member 48, now assumed to be out of engagement with 49 and in contact with 64. Departing now for 10 a moment, the other conductor of these open parallel paths may be traced from armature 55 by wire 54, to junction 53, wire 52, to junction 51, where the circuit again divides one conductor going to test switch 15 member 83 and the other to lock switch member 49 which as heretofore stated is not in engagement with 48, thus providing two paths by the closure of either one of which current will be supplied, whereby control 20 electro-magnet 80 may become temporarily energized.

If now the user deems it desirable to test the system, he will press test button 84 disposed on the front side of casing 99. This 25 will open the ground connection to relay coils 7 and 8, by means of switch members 17 and 16 and close a normally open shunt across upper contact 73 and armature 55, as follows: from contact 73, to wire 74, junction 19, wire 18, switch member 17, switch member 86, wire 85, junction 53, wire 54, to armature 55. The closure of the circuit of 30 electro-magnet 80 associated with armature 55 and upper contact 73 normally takes 35 place by the attraction of armature 55 when both protective circuits are complete, but when one or both wires of the protective circuits are ruptured or crossed or grounded, this function is performed by the test device 40 vice when a test is made.

When the button 84 causes 86 and 17 to make circuit, it also closes the circuit between switch members 82 and 83 as will be observed by referring to Fig. 2. Switch 45 members 83 and 17 are connected by means of insulating strip 100, so that, as pressure is applied to button 84, 17 is caused to break connection with 16 and make connection with 86 while switch member 83 will by the 50 same operation make connection with 82.

With the system in the status just described, switch members 82 and 83 normally form an open shunt around combination lock switch members 48 and 49 as previously described. It therefore follows that when the test button 84 is operated to make connection between 82 and 83, this will have the same effect upon the system for testing purposes as manipulating the combination lock 60 to move its bolt to the "Night" side, and aside from other inherent advantages, eliminates the necessity of disclosing the combination to a repair man who may be repairing or inspecting the system. The test button 65 84 having been pressed as just described,

and the two outside conductors, 4-6 and 9 from the source of energy through the guarded structure being complete and coils 7 and 8 now attracting armature 55, the shunt circuit of coils 23 being open by reason 70 of the armature lever 26 of electro-magnet 80 being in its dotted line position, current will be caused to flow through control electro-magnet 80, which will move its armature 26 to the position shown in the drawing, thus opening the circuit of electro-magnet 80 and closing the shunt of the protective circuits through coils 23, and also by the same operation closing a conductor of the circuit closer as previously described. 75 The audible signal will not be energized, and this will at least indicate to the person testing that the coils 7 and 8 are energized and consequently that the guarded circuit is in perfect condition, for if coils 7 and 8 were not energized, armature 55 would fall and cause the signal 59 to sound. 80

Now assuming that the user also desires to test the working condition of the audible signal and its associated circuits, he will open any exit, let us say for example, the door which he proposes to use as a means of egress from the guarded structure after setting the system. With this exit open, coils 7 and 8 become de-energized; armature 55 95 falls and is also attracted by coils 23, the circuit therethrough being still active. 95

Returning to the instrument casing, he again actuates the testing device. This obtains the following results: Remembering that switch members 48 and 49 are separated, because lock 62 is on the "Day" side, we see that the engagement of armature 55 with contact 29 does not close a circuit. But as test switch members 82 and 83 are brought into contact with each other, a circuit is closed around the lock and through the circuit closer as follows: from armature 55, to contact 29, wire 30, contact member 31, contact piece 77, contact member 32, wire 33, junction 34, circuit closer coil 35, wire 36, contact 37, armature 38, wire 39, junction 40, wire 41, junction 42, wire 72, alarm battery 43, junction 44, wire 45, junction 46, wire 101, switch member 82, switch member 83, junction 51, wire 52, junction 53, wire 54, to armature 55. The closure of the circuit which has just been traced will cause the energization of coil 35 which will attract toward itself armature 38, thus opening the circuit of the circuit closer and making engagement with contact 56, closing the circuit of the signaling means, which has been previously traced. 115

In order to restore the system to its previous disconnected position, the user has only to actuate plunger 68, so as to move armature lever 26 to its dotted line position and the signal will be silenced. 120

Now the combination lock 62 is manipu- 130

lated so as to throw its bolt to the "Night" side 94, and as the bolt moves to its proper position, lock switch member 48 will be released from connection with its coöperant 5 contact 64 and make contact with 49, and this will be indicated to the operator by means of the indicator 95 being moved by lock bolt 63 to point toward the word "Night" at 94, thus readily giving visual assurance to the operator, that the system is 10 actually set for effective operation.

The operator now leaves the guarded structure by means of the exit previously selected and which is now ajar. As he 15 leaves the guarded structure, his closing the door of the exit closes both protective circuits, and armature 55 is thereby pulled up toward coils 7 and 8.

The circuit closer control electro-magnet 20 80 is momentarily energized by the closure of the following circuit: from battery 43, to junction 44, wire 45, junction 46, wire 47, switch member 48, switch member 49, wire 50, junction 51, wire 52, junction 53, wire 54, 25 armature 55, upper contact 73, wire 74, junction 19, wire 102, contact member 75, contact piece 77, contact member 76, wire 79, electro-magnet 80, wire 81, junction 42, wire 72, to battery 43. Magnet 80 then moves its 30 armature to effect the opening of its own circuit and to provide conducting means, such as contact piece 77 for lower contact 29 of the main electro-magnet, and such as lever 26 for the shunt of the protective circuit, so that if there be any surreptitious interference with the guarded structure the shunt will become effective to coöperate with the other means described to sound the audible signal.

40 Now referring to the function to be performed by test switch members 17 and 86, in order to clearly describe the useful purpose of which, let us assume that the circuit of the guarded structure has been opened 45 by an authorized person entering for instance in the morning. Assume also that the combination lock has been operated and the indicator 95 rests on the "Day" side 93, the alarm having been regularly silenced as 50 previously described, now suppose that during the interval between opening the guarded circuit for the day and closing for the night one wire of the protective circuit has become broken in any manner; now when 55 button 84 of the testing device is operated in the manner described above to test the system it separates switch members 16 and 17, and the ground connection of the protective circuit is thereby opened and armature 60 55 is allowed to fall, and will fall to its lower or retracted position provided it is not maintained attracted by any residual magnetism; but assuming no residual magnetism to exist in the coils, the armature will fall into engagement with lower contact 29.

As the test switch members 17 and 86, and 65 83 and 82 are brought into engagement respectively, a circuit is completed for circuit closer control magnet 80 as follows: from 70 battery 43, to junction 44, wire 45, junction 46, wire 101, switch members 82 and 83, junction 51, wire 52, junction 53, wire 85, switch members 86 and 17, wire 18, junction 19, wire 102, contact member 75, contact 75 piece 77, contact member 76, wire 79, magnet 80, wire 81, junction 42, wire 72, to battery 43. Magnet 80 is momentarily energized and the shunt circuit is thereby closed to overcome any possible residual magnetism in the cores of coils 7 and 8. As magnet 80 has also brought contact members 81 and 32 into electrical engagement with each other the signal will be sounded, thus indicating to the operator that a fault exists in 85 the protective circuit, notwithstanding which the operator may defer having the fault corrected until a more opportune time, and proceed as before to restore and then set the system and leave the guarded structure under the electric protection of one of 90 the protective circuits.

If an attempt should be made to surreptitiously gain entrance to the guarded structure, by removing the alarm housing, and 95 destroying the signal before actually forcing an entrance into the guarded structure; this would necessitate drilling a hole through the metal housing, or a metal tool of some character would necessarily be employed. 100 With my arrangement, if a metal which is a conductor of electricity is brought into contact with the housing and the signal, a circuit will be formed as follows, to actuate the circuit closer and operate the alarm:

From metal housing 87 by means of a wire 88, connected to the housing at 89, to junction 34, through coil 35, wire 36, to contact 37, circuit closer armature 38, wire 39, to junction 40, wire 41, junction 42, wire 72, 110 battery 43, junction 44, wire 61, to alarm binding post 60 which is not insulated from the structure of bell 59, thus energizing the circuit closer electro-magnet and sounding the signal. It may also be here stated that 115 if the housing itself is brought into contact with bell structure 59, the same results will obtain.

As will be apparent to one skilled in the art to which this invention pertains, many 12 changes may be made in the general scheme of circuiting as well as in the devices herein described and diagrammatically illustrated without departing from the spirit of the invention.

I claim:

1. In a burglar alarm system, a source of energy and a protective circuit, said protec-

2. A protective circuit including said source of energy, a guarded structure, and electro-magnet means, a by-path including a second electro-magnetic means in parallel with said first 5 electro-magnet means, said by-path remaining closed while said system is set, and circuit closing means actuated thereby upon interference with the guarded structure and consequent action of the first mentioned 10 electro-magnet means.
3. In a burglar alarm system, a guarded structure, a protective circuit therefor including a source of energy, said circuit being closed while in protective condition, 15 there being included in said protective circuit electro-magnetic means, and circuit closing means actuated thereby upon the closure of the protective circuit.
4. In a burglar alarm system, a protective circuit including a source of energy, a guarded structure, and electro-magnetic means, circuit closing means, and a circuit therefor, including an alarm, an electro-magnet to actuate said circuit closing means, 20 and a second electro-magnet momentarily energized by the protective circuit to close the circuit of said actuating electro-magnet.
5. In a burglar alarm system, a protective circuit including a source of energy, a guarded structure, and electro-magnetic means, circuit closing means and a circuit therefor, an electro-magnet momentarily energized by the protective circuit to actuate 30 said circuit closing means, and an alarm adapted to be energized after actuation of said circuit closing means.
6. In a burglar alarm system, an electro-magnet, a circuit including the armature of said electro-magnet, a source of energy and 40 a second electro-magnet, circuit closing means and an audible alarm adapted to be controlled by said second electro-magnet, said audible alarm having a metallic casing, an open shunt around said armature, 45 said open shunt including the casing for the audible alarm, and the structure of the audible alarm, said shunt being adapted to energize the last mentioned electro-magnet when conducting means is interposed between 50 the structure of the audible alarm and the casing substantially as described.
7. In a burglar alarm system, an electro-magnet, a circuit including the armature of said electro-magnet, a source of energy and 55 a second electro-magnet, an audible alarm and circuit closing means in the circuit thereof adapted to be controlled by said second electro-magnet, said audible alarm having a metallic casing, an open 60 shunt around said armature, said open shunt including the casing for the audible alarm, and the structure of the audible alarm, said shunt being adapted to energize said second electro-magnet when conducting means is interposed from the structure of the audible alarm to the casing, thereby to stimulate the audible alarm.
8. In a burglar alarm system, the combination with a signal of a protective circuit including a plurality of conducting means, 65 including a guarded structure, a lock controlled switch for disabling said signal, and testing means normally operative to actuate said signal to indicate whether the system is in proper working order, while said switch is in disabling position, substantially as described.
9. In a burglar alarm system, the combination with an alarm, of a protective circuit including a guarded structure, said alarm 70 being adapted to be energized upon interference with the guarded structure, a lock controlled switch for disabling said alarm, and a test device adapted to operate said alarm as a trouble signal when the test device is operated while said switch is in disabling position and a fault exists in the system.
10. In a burglar alarm system, the combination with an alarm, of a protective circuit including a guarded structure, said alarm being adapted to be energized upon interference with the guarded structure, a lock controlled switch for disabling said alarm, a test device adapted to operate said 80 alarm as a trouble signal when the test device is operated while said switch is in disabling position, and a fault exists in the system, and means in the protective circuit whereby the system may be operatively 85 connected, notwithstanding such fault and trouble signal.
11. In a burglar alarm system, in combination, a three-wire electro-magnet and armature therefor, a testing device for opening one of the three wires and thereby effecting the retraction of said armature in case another wire has been broken, a circuit closing circuit arranged to be closed by said armature in its retracted position, 90 and a signal controlled by said last named circuit.
12. In a burglar alarm system, in combination, a three-wire electro-magnet and armature therefor, a testing device for opening one of the three wires and thereby effecting the retraction of said armature in case another wire has been broken, a circuit closing circuit arranged to be closed by said armature in its retracted position, a lock, and lock contacts in said circuit closing circuit held separated by the lock in its 95 unlocked position, and a signal controlled by said last named circuit.
13. In a burglar alarm system, in combination, a three-wire electro-magnet and armature therefor, a testing device for opening one of the three wires and thereby effecting the retraction of said armature in case another wire has been broken, a circuit closing circuit arranged to be closed by said armature in its retracted position, a lock, and lock contacts in said circuit closing circuit held separated by the lock in its unlocked position, and a signal controlled by said last named circuit.

- ing the retraction of said armature in case another wire has been broken, a circuit closing circuit arranged to be closed by said armature in its retracted position, a lock, lock 5 contacts in said circuit closing circuit held separated by the lock in its unlocked position, a signal controlled by said last named circuit, and a testing device for closing the circuit closing circuit independently of said 10 lock contacts.
13. In a burglar alarm system, in combination, a three wire electro-magnet and armature therefor, a testing device for opening one of the three wires and thereby effecting the retraction of said armature in case another wire has been broken, a circuit closing circuit arranged to be closed by said armature in its retracted position, a lock, lock contacts in said circuit closing circuit 15 held separated by the lock in its unlocked position, a signal controlled by said last named circuit, said lock contacts including two contacts held in engagement when the lock is open, and a restoring circuit passing 20 through said last named contacts for restoring said circuit closing circuit.
14. In a burglar alarm system, in combination, a three wire electro-magnet having an armature, a second electro-magnet, a shunt circuit of said three wire electro-magnet passing through said second electro-magnet, a hand controlled switch, a testing circuit 25 closed by said switch in one position thereof and including an electro-magnet for moving said switch into a position to close the circuit for said second electro-magnet, and a circuit closing circuit closed by said armature when released by said first named 30 magnet.
15. In a burglar alarm system, in combination, a three wire electro-magnet having an armature, a second electro-magnet, a shunt circuit of said three wire electro-magnet passing through said second electro-magnet, a hand controlled switch, a testing circuit 35 closed by said switch in one position thereof and including an electro-magnet for moving said switch into a position to close said shunt circuit, a circuit closing circuit closed by said armature when released by said first named magnet.
16. In a burglar alarm system, in combination, a three wire electro-magnet having an armature, a second electro-magnet, a circuit for said second electro-magnet, a hand controlled switch, a testing circuit 40 closed by said switch in one position thereof and including an electro-magnet for moving said switch into a position to close said shunt circuit, a circuit closing circuit closed by said armature when released by said first named magnet, two of the three 45 wires protecting an exit, and means for opening the third wire with said exit closed to ascertain whether there is current in both the other wires.
17. In a burglar alarm system, in combination, a three wire electro-magnet having an armature, a second electro-magnet, a circuit for said second electro-magnet, a hand controlled switch, a testing circuit 50 closed by said switch in one position thereof and including an electro-magnet for moving said switch into a position to close the circuit for said second electro-magnet, and a circuit closing circuit closed by said armature when released by said first named 55 magnet.
- In testimony whereof I affix my signature.
SIMON B. HESS.
